Primary Examiner—Robert M. Spear

Assistant Examiner—Susan Bennett Hattan

(57) **CLAIM**

We claim the ornamental design for a closure shell, as shown and described.

DESCRIPTION

FIG. 1 is a perspective view of a closure shell showing our new design;

FIG. 2 is a front elevational view thereof, the rear elevational view and two side elevational views being identical; and, FIG. 3 is a top plan view thereof, the bottom of the closure shell forming no part of the claimed design.
